WEB FEED CONTROL FOR AUTOGRAPHIC
REGISTERS

Victor William Garwood, London, England, assignor, by mesne assignments, to American Sales Book Company, Inc., a corporation of Delaware

Application February 6, 1935, Serial No. 5,173
In Great Britain February 20, 1934

35 Claims. (Cl. 282—16)

This invention relates to improvements in autographic registers, and more particularly to an improved mechanism for facilitating threading of the webs or record strips into operative position with relation to the web-feeding mechanism. The improvements of the invention, according to the present disclosure, are embodied in an autographic register of the type disclosed in Patent No. 1,658,127, issued to Clarence L. Johnston on February 7, 1928.

One of the advantages of a machine of the above type is that in use one or more webs or sets of forms bearing copies of the memoranda are passed automatically into a locked filing compartment to which access can only be obtained by a person having the key. In the usual type of machine, however, the feed discs and the upper feed roller which cooperate to feed the webs are arranged adjacent to the filing compartment and the webs pass between the discs and rollers to a dividing plate where the lowest web or webs is or are deflected and passed downwardly through a slot into the locked compartment. To reload the machine, however, it is necessary to swing the upper feed roller away from the feed discs to enable the fresh set of webs to be correctly aligned over the feed discs with their forward edges over and under the dividing plate as desired.

In the known machine the upper feed roller is carried in a housing which is pivotally mounted and which is normally held locked in the operative position, for example, by a part of the locked filing compartment. Thus to reload the machine, the filing compartment must first be unlocked to enable the housing to be swung back, thus giving access to the webs in the compartment.

It is not always desirable that the person who reloads the machine should have access to the locked compartment.

One of the objects of the present invention is to provide a machine of the above described type with means whereby the machine can be reloaded without the necessity of unlocking the filing compartment, or of removing the upper feed roller from contact with the lower feed discs, or taking it out of mesh with its own drive.

A further object of the invention is to so arrange the machine that access to the passage or slot through which the web passes into the locked filing compartment is made impossible, thus preventing tampering with the machine in this respect. In addition the invention includes improved means for guiding the webs between the feed discs and upper roller and through the aforesaid passage or slot with the object of pre-

venting tearing or jamming and the possibility of a torn or uneven web upsetting the normal working of the machine. Further improvement is to make it impossible for a web intended to be issued out of the machine to change its path by fouling the dividing plate and becoming deflected into the locked up compartment.

According to a preferred embodiment of the invention, in an autographic register of the type referred to, the upper feed roller is carried in a displaceable housing normally held locked in the position in which the roller is in operative association with the feed discs, and the dividing plate separating the web or webs intended to pass into the filing compartment from those which are to be issued from the register, is extended rearwardly toward the writing plate. The rear edge of the dividing plate preferably projects at the rear of the upper roller housing.

Further, in the arrangement according to the preferred embodiment of the invention, a complete closure is effected of the passage by which the lowest web or webs pass into the filing compartment and access to this passage can only be obtained when the upper feed roller housing is unlocked and displaced.

Other objects and advantages of the invention will be pointed out in the following detailed description of certain illustrative but preferred embodiments of the invention and will be in part obvious in connection therewith.

For a more complete understanding of the nature and objects of the invention reference is had to the accompanying detailed description and to the drawings, in which:

Fig. 1 is a vertical, longitudinal sectional view with parts of the improved register mechanism shown in side elevation;

Fig. 2 is a fragmentary plan view of Fig. 1 with the upper feed roll and housing therefor removed;

Fig. 3 is an enlarged side elevation of the web deflector or dividing plate;

Fig. 4 is a fragmentary plan view of the deflector plate showing a modified construction; and

Fig. 5 is a fragmentary side elevation of the deflector plate of Fig. 4.

Referring to the drawings, the writing plate 1 is hingedly carried on the side frames of the apparatus and over which the paper webs are arranged to be moved forwardly, i. e. to the left as viewed in the drawings, by feed discs 2 and an upper feed roller 3. This roller is carried in a housing 4 pivotally mounted on the side frames of the apparatus by arms 5 pivoted at 5'. A

- dividing or deflector plate 6 is preferably hingedly mounted on the side frames and is intended to separate and guide the lower web or webs to a filing compartment 7 which is normally locked. 5 The deflector plate 6 may be mounted in position by means of a supporting bar 6a connected to one edge of the plate and having supporting bearings 6b at its opposite ends rotatably engaging bearings in the opposite side frames. 10 In the present construction, the dividing plate 6 is carried backwardly so that the upper and lower paper webs are separated by the plate before they reach the feed discs 2 and roller 3. The plate 6 is also carried forwardly so that its front 15 edge is adapted to be covered by the rear edge of the hingedly mounted top plate 8 of the filing compartment 7. By means of notches in the upper edges of the arms 5 and the cooperating adjacent corners of the cover or top plate 8 the 20 roll carrier or housing 4 is maintained in its operative position when the top plate is locked to close the compartment 7.

By carrying the dividing plate backwards to a position in close proximity to the front edge of 25 the writing plate 1, the passage by which the lower web or webs pass to the filing compartment is effectively closed at the rear while the forward end of this passage, as is clear from the drawings, is also closed. When the housing 4 30 is locked in the operative position as shown in Fig. 1, the rear edge of the dividing plate 6 preferably projects beyond the housing 4. A clearance is, of course, allowed between the housing and the plate to permit the upper webs 35 to pass to the feed discs 2 and roller 3. The openings 9 in the plate to permit the feed discs and rollers to cooperate are of an improved shape as will be described below. A slot 10 is also provided in the plate to permit a gear wheel 40 on the spindle 11 carrying the discs 2 to mesh with a gear wheel (not shown) on the spindle carrying the roller 3 for driving the spindle. A further slot 12 in the plate provides for the passage of the fold directing finger or hook 13 on 45 the disc 2a mounted on the shaft 11, said finger being adapted to enter perforations in a lower web to direct it downwardly into the compartment 7. The upper webs pass over the upper surface 50 of the plate 6 and issue on to the top plate 8 in known manner. The arrangement of the feed controlling apertures and fold directing apertures of the webs or strips may be substantially as disclosed in the above mentioned Johnston patent. By hingedly mounting the plate 6 as 55 shown the severance of the web and the collection of written copies from the filing compartment are greatly facilitated.

From the foregoing it will be seen that the passageways for the strips at the feeding mechanism are oppositely disposed, one above another at the opposite sides of the deflector plate 6. The strips or webs, when being threaded into the feed mechanism and when being fed forwardly thereby extend through these passageways, the web or webs to be issued from the machine being in the upper passageway and the web or webs being filed in the compartment 7 being in the lower passageway. It will be seen in Fig. 1 that both of the web passageways have their receiving openings positioned at the rear of the web deflecting device. This arrangement is of material advantage when threading the webs into the grip of the feed mechanism, since said webs may thus be easily entered through the 75 receiving openings into the passageways and then

into the feed grip without raising the housing 4 and without adjusting any other parts of the mechanism. The downwardly inclined forward margin of the writing plate or platen 1 also aids in guiding the file web into the lower passage- 5 ways.

Also from the above disclosure it will be seen that the complete web deflecting device for separating the webs and directing them to issue over the top plate 8 and to be filed in the compartment 7, may be considered as comprising not only the deflector plate 6 with its guides 14 or 14a hereinafter referred to (when these are used), but also the associated parts such as the housing 4 and the upper and lower web receiving pas- 15 sageways above and below the deflector plate 6.

In order to enable the feed starting blocks 2b on the feed discs 2 to grip a large area of the paper webs and thus function properly on possibly torn webs and avoid jamming, the openings 20 9 of the dividing or deflector plate 6 are made wide. The rear edge of each opening 9 is preferably straight along a transverse line lying near the rear edge of the dividing plate 6, but the forward part of each opening 9 is curved or 25 arched as seen in plan in Fig. 2. This shape, which may be approximately the segment of a circle or an ellipse, is found to be effective in preventing the perforated edges or torn leading edges of the webs from catching in the 30 openings and tending to jam or foul the feed. By means of this structural arrangement it will be seen that the deflector plate at the forward terminal of said opening presents a concave marginal portion which is directed toward the ad- 35 vancing webs as the latter are moved forwardly by operation of the feeding mechanism. The underside of the deflector plate 6 may be furnished with guides 14, formed by curved surfaces or plates, the function of which is to guide 40 and keep the front edges of the webs destined for the filing compartment, away from the edges of the openings 9 in the plate 6, against which they might otherwise be caught. In place of the curved plate 14, pieces of spring wire 14a ex- 45 tends around the parts of the openings adjacent to the center of the plate and slightly projecting therefrom may be employed, as shown in Figs. 4 and 5. An additional curved guide surface such as the plate or plates 14b may also 50 be arranged behind the guides 14 to direct the webs into the filing compartment.

If desired the openings 9 may be made shorter at the forward or curved ends than those shown in Fig. 2, and thus minimize the desirability of 55 fitting guides 14 or 14a for the lower webs. While an advantage arises as far as the lower webs are concerned, the shorter openings increase the possibility of jamming by the top webs. The dimensions of the openings 9 may, therefore, be chosen to effect a compromise and be such that while the chances of fouling and jamming may not be wholly removed, the fitting of the guide 14, 14a on the underside of the plate 6 may be dispensed with. It is preferred, however, to employ 60 the larger size of openings and to fit suitable guides.

The openings for the starting blocks 2b may be carried back to cut the rear edge of the plate 6, as shown at 9a in Fig. 4, and an important 70 advantage is obtained thereby. This lies in the fact that the apparatus may be loaded when the closed compartment 7 and, therefore, the housing 4 are locked, so that the machine operator can carry out such loading without the attend- 75

5 ance of a person authorized to open the compartment 7. To carry out the loading operation, the usual apertured writing plate cover (not shown) is swung back, giving access to the writing plate 1. The magazine (also not shown) is opened and the new webs threaded through a usual tension device or grid such, for example, as shown in the Johnston patent mentioned.

10 To assist in obtaining correct alignment of the webs, aligning pins 15 are adapted to be projected up through holes in the writing plate 1 by the operation of a suitable handle 16a fixed to a spindle 16, and a rock arm 17 fixed to said spindle, as later more fully described. The pins 15 are 15 disposed apart by the distance between the usual perforations or slots in the forms into which the web is divided, as shown in the Johnston patent, and the new webs are placed on the writing plate with the pins extending through the marginal 20 holes in, say, the second forms in each web. The ends of the webs intended for the locked compartment 7 are then inserted under the rear edge of the plate 6, one at a time, each web being introduced in turn between the discs 2 and 25 the feed roller 3 by a small movement of the usual operating handle keyed to the drive shaft or spindle 11. Such movement of the operating handle is sufficient to draw in the slack in the web between the pins 15 and the roller 3, it being 30 understood that the distance between the pins 15 and the roller 3 is chosen so that when the slack has been taken up the holes in the leading edge of the web arrive between the feed discs and the upper roller so that the discs cannot grip 35 the web until the feed starting blocks 2b on the discs come into operation. The upper webs are then introduced between the feed discs 2 and the roller 3 in similar manner but above the plate 6. The aligning pins 15 are then depressed, for 40 example, by means of the handle on the spindle 16. The forward movement of the operating handle already begun during the loading process is now completed which brings the feed blocks 2b into contact with all of the webs just loaded 45 aligning them ready for issue by the normal operation of the machine.

50 In Fig. 1 is shown an arrangement by which the aligning pins 15 are so arranged that the operator can only turn them up when the operating handle of the feed mechanism is in such a position that the feed starting or driving blocks 2b on the feed discs 2 are in an inoperative position. The pins 15 when up are held in this position until the operating feed handle is turned to a 55 position in which the blocks are about to again reach the position when they are opposite the feed roller 3, at which moment the pins are retracted to release any webs that may be thereon. This prevents tearing of the webs on the aligning pins 15.

60 The arrangement can be clearly seen in Fig. 1 in which the pins 15 are carried on a plate or arm 18 pivotally mounted on a cross-shaft 19 carried on the machine frame. Pivotally mounted 65 on a bracket 18' on the plate 18 is a downwardly depending arm 20 having a hooked end 20'. A shoulder 21 is also formed on the arm 20. The arm 20 is arranged to move in a slot in a fixed member 22 to which is rigidly attached a locking bar 23. The pin 15 may be raised to its operative 70 position by turning the handle 16a, swinging the arm 17 into engagement with a lug 18a on the supporting plate 18. The pins 15 are held in their operating position by cooperation of the shoulder 21. Pivotally connected to the arm 20

75 is a link 24 pivotally connected to one arm of a bell crank lever 25 carried on a fixed pivot 25a. The end of the other arm of the lever 25 is provided with two projections 26, 27. Pins 28, 29 are arranged on concentric circles of different 5 radii on the disc 2a and are arranged to cooperate with the projections on the end of the lever 25 as will be described.

The disc 2a is arranged to rotate in a counter-clockwise direction as indicated by the arrow 10 in Fig. 1. When the lever 17 is moved up by means of the handle on the spindle 16 the pins 15 and the plate 18 also move upwardly. If the lever 25 is in the position shown in full lines, to which position it is biased by a spring 25b, the 15 arm 20 moves to the upper position shown in dotted lines, and by means of the shoulder 21 engaging with the member 22 is held in this position. It will be appreciated that the spring 25b which biases the lever 25 moves the arm 20 for 20 wardly so that the shoulder 21 engages the plate 22. When the disc 2a is rotated, some time before the feed starting blocks 2b reach their operative position, the pin 28 strikes the projection 26 and rotates the lever 25, thus swinging the arm 25 25 to the right so that the shoulder 21 is disengaged, allowing the plate 18 and pins 15 to drop. The pin 28, which in the normal operation of the machine is the first to engage with the lever 25, is only able to displace the latter far 30 enough to insure the release of the hanging arm 20 from engagement with the plate 22. A further movement of the pin 28 releases the lever 25, which drops back to its normal position under the influence of spring 25b as shown by the full 35 line. The function of the pin 29 is to repeat the displacement of the lever 25 but to carry it further than in the case of pin 28, so that the hook 20' at the end of arm 20 engages with the locking bar 23 and prevents the plate 18 from being 40 moved upwardly from its last inoperative position.

The two pins 28 and 29 thus operate to prevent lifting of the plate 18 and the pins 15 while the blocks 2b on the feed discs are approaching or are in their operative feeding position, as in 45 this position it is not possible to reload new webs into the machine. The position and arrangement of pin 28 insure that the arm 20 is tripped and the plate 18 dropped before the feed starting blocks have time to drag the forms that for 50 loading purposes have been threaded on the pins 15, the loading pins 15 carried by plate 18 being also dropped automatically before the feeding discs start to move the forms.

55 Since certain changes may be made in the above construction and different embodiments of the invention could be made without departing from the scope thereof, it is intended that all matter contained in the above description or shown in the accompanying drawings shall be interpreted 60 as illustrative and not in a limiting sense.

Having now particularly described my invention, the following is claimed:

1. In an autographic register, in combination, 65 feed mechanism having a feed grip for gripping and feeding the webs, a web-deflecting device for separating webs emerging from the feed mechanism into different courses, said deflecting device being provided with oppositely disposed web-receiving passageways opening to the rear of 70 said feed grip and accessible at the rear thereof for web reception, said feed mechanism having rotary web feed elements with said feed grip therebetween for gripping and feeding the webs, said web-deflecting device including a web-de- 75

flecting plate positioned adjacent to said feed grip and having an opening in which the feed grip portion of one of said rotary elements is positioned, web-starting means on one of said rotary feed elements adapted to enter said opening, web-holding means positioned for cooperation with parts of the webs positioned rearwardly from the feed mechanism for holding webs being threaded into said feed mechanism, and means operated by the web feeding operation of said feed mechanism for releasing said holding means when said starting means moves into proximity to said opening.

2. In an autographic register, in combination, feed mechanism having a feed grip for gripping and feeding the webs, a web-deflecting device for separating webs emerging from the feed mechanism into different courses, said deflecting device being provided with oppositely disposed web-receiving passageways opening to the rear of said feed grip and accessible at the rear thereof for web reception, said feed mechanism having rotary web feed elements with said feed grip therebetween for gripping and feeding the webs, said web deflecting device including a web-deflecting plate positioned adjacent to said feed grip, a web-starting lug on one of said feed elements, web-holding means for holding webs being threaded into feeding position, means operated by the web feeding operation of said feed mechanism for operating said holding means to release webs held thereby as said starting lug moves into proximity to said feed grip, and automatic means controlled by the feed mechanism for preventing setting of said holding means in web-holding condition when said starting lug is about to initiate web-starting action.

3. In a device of the character described, in combination, strip feeding mechanism operative to feed the strips into operative position, strip positioning means for positioning strips for entry into feeding relation with reference to said feeding mechanism, and means operated by said feeding mechanism for controlling the operative position of said strip positioning means.

4. In a device of the character described, in combination, strip feeding mechanism operative to feed the strips into operative position, strip engaging strip positioning means for positioning strips for entry into feeding relation with reference to said feeding mechanism, and means controlled by feeding actuation of said feeding mechanism for retracting said positioning means out of strip engaging position at a predetermined position of the feeding mechanism.

5. In a device of the character described, in combination, strip feeding mechanism operative to feed the strips into operative position, strip engaging strip positioning means for positioning strips for entry into feeding relation with reference to said feeding mechanism, means operated by said feeding mechanism for controlling the operative position of said strip positioning means, and an independent manual means for setting said strip positioning means in strip engaging position independently of said feeding mechanism.

6. In a device of the character described, in combination, strip feeding mechanism operative to feed the strips into operative position, strip engaging strip positioning means for positioning strips for entry into feeding relation with reference to said feeding mechanism, means controlled by feeding actuation of said feeding mechanism for retracting said positioning means out of strip engaging position at a predetermined po-

sition of the feeding mechanism, and an independent manual means for setting said strip positioning means in strip engaging position independently of said feeding mechanism.

7. In a device of the character described, in combination, strip feeding mechanism, strip engaging strip positioning means for positioning strips in feeding relation with reference to said feeding mechanism, means operated by said feeding mechanism for controlling the operative position of said strip positioning means, an independent manual means for setting said strip positioning means in strip engaging position independently of said feeding mechanism, and means controlled by the feeding mechanism for preventing movement of said strip positioning means into strip engaging position.

8. In a device of the character described, in combination, strip feeding mechanism, strip engaging strip positioning means for positioning strips in feeding relation with reference to said feeding mechanism, means controlled by feeding actuation of said feeding mechanism for retracting said positioning means out of strip engaging position at a predetermined position of the feeding mechanism, an independent manual means for setting said strip positioning means in strip engaging position independently of said feeding mechanism, and means controlled by the feeding mechanism for preventing movement of said strip positioning means into strip engaging position at predetermined intervals.

9. In a device of the character described, in combination, strip feeding mechanism, strip engaging strip positioning means for positioning strips in feeding relation with reference to said feeding mechanism, independent operating means operable independently of the feeding mechanism for setting said positioning means in operative strip engaging position, and means controlled at predetermined intervals by actuation of the strip feeding mechanism for retracting said positioning means from strip engaging position.

10. In a device of the character described, in combination, strip feeding mechanism, strip engaging strip positioning means for positioning strips in feeding relation with reference to said feeding mechanism, independent operating means operable independently of the feeding mechanism for setting said positioning means in operative strip engaging position, means for holding said positioning means in its operative strip engaging position, and means controlled at predetermined intervals by actuation of the strip feeding mechanism for releasing said holding means and retracting said positioning means from strip engaging position.

11. In a device of the character described, in combination, strip feeding mechanism, strip engaging strip positioning means for positioning strips in feeding relation with reference to said feeding mechanism, independent operating means operable independently of the feeding mechanism for setting said positioning means in operative strip engaging position, means for holding said positioning means in its operative strip engaging position, and operating connections between said feeding mechanism and said holding means for releasing the latter at a predetermined point in the cycle of operation of the feeding mechanism.

12. In a device of the character described, in combination, strip feeding mechanism, strip engaging strip positioning means for positioning strips in feeding relation with reference to said feeding mechanism, independent operating

means operable independently of the feeding mechanism for setting said positioning means in operative strip engaging position, means controlled at predetermined intervals by actuation of the strip feeding mechanism for retracting said positioning means from strip engaging position, and a locking device operatively controlled by said feeding mechanism for locking said positioning means against assuming a strip controlling position at a certain position of the feeding mechanism.

13. In a device of the character described, in combination, strip feeding mechanism including a feeding member having a strip gripping, feeding periphery adjacent to which is a strip engaging, starting lug and including also a pressure roll cooperating with said periphery and starting lug to form a feeding grip, strip engaging strip positioning means for positioning strips in feeding relation with reference to said feeding mechanism, and means controlled by feeding actuation of said feeding mechanism for retracting said positioning means from strip engaging position prior to engagement of said starting lug with 25 said pressure roll during a feeding operation.

14. In a device of the character described, in combination, strip feeding mechanism including a feeding member having a strip gripping, feeding periphery adjacent to which is a strip engaging, starting lug and including also a pressure roll cooperating with said periphery and starting lug to form a feeding grip, strip engaging strip positioning means for positioning strips in feeding relation with reference to said feeding mechanism, and means controlled by feeding actuation of said feeding mechanism for retracting said positioning means from strip engaging position prior to engagement of said starting lug with said pressure roll during a feeding operation, and an independent manual means for setting said strip positioning means in strip engaging position independently of said feeding mechanism.

15. In a device of the character described, in combination, strip feeding mechanism including a feeding member having a strip gripping, feeding periphery adjacent to which is a strip engaging, starting lug and including also a pressure roll cooperating with said periphery and starting lug to form a feeding grip, strip engaging strip positioning means for positioning strips in feeding relation with reference to said feeding mechanism, and means controlled by feeding actuation of said feeding mechanism for retracting said positioning means from strip engaging position prior to engagement of said starting lug with said pressure roll during a feeding operation, and means controlled by the feeding mechanism for preventing movement of said strip positioning means into strip engaging position immediately prior to engagement of said starting lug with said pressure roll during a feeding operation.

16. In a device of the character described, in combination, strip feeding mechanism including a feeding member having a strip gripping, feeding periphery adjacent to which is a strip engaging, starting lug and including also a pressure roll cooperating with said periphery and starting lug to form a feeding grip, strip engaging strip positioning means for positioning strips in feeding relation with reference to said feeding mechanism, and means controlled by feeding actuation of said feeding mechanism for retracting said positioning means from strip engaging position prior to engagement of said starting lug with said pressure roll during a feeding opera-

tion, an independent manual means for setting said strip positioning means in strip engaging position independently of said feeding mechanism, and means controlled by the feeding mechanism for preventing movement of said strip positioning means into strip engaging position immediately prior to engagement of said starting lug with said pressure roll during a feeding operation.

17. In a device of the character described, in combination, strip feeding mechanism including a feeding member having a strip gripping, feeding periphery adjacent to which is a strip engaging, starting lug and including also a pressure roll cooperating with said periphery and starting lug to form a feeding grip, strip engaging strip positioning means for positioning strips in feeding relation with reference to said feeding mechanism, means for setting said strip positioning means in operative strip engaging position 20 independently of said feeding mechanism, means for holding said strip positioning means in its set condition and means operatively connected to said feeding mechanism for releasing said holding means before said starting lug reaches 25 strip gripping engagement with said pressure roll during a feeding operation.

18. In a device of the character described, in combination, strip feeding mechanism including a feeding member having a strip gripping, feeding periphery adjacent to which is a strip engaging, starting lug and including also a pressure roll cooperating with said periphery and starting lug to form a feeding grip, strip engaging strip positioning means for positioning strips in feeding relation with reference to said feeding mechanism, means for setting said strip positioning means in operative strip engaging position independently of said feeding mechanism, means for holding said strip positioning means in its set condition, means operatively connected to said feeding mechanism for releasing said holding means before said starting lug reaches 30 strip gripping engagement with said pressure roll during a feeding operation, 35 and means controlled by the feeding mechanism for preventing movement of said strip positioning means into strip engaging position independently of said feeding mechanism, means for holding said strip positioning means in its set condition, means operatively connected to said feeding mechanism for releasing said holding means before said starting lug reaches 40 strip gripping engagement with said pressure roll during a feeding operation, and means controlled by the feeding mechanism for preventing movement of said strip positioning means into strip engaging position independently of said feeding mechanism, means for holding said strip positioning means in its set condition, means operatively connected to said feeding mechanism for releasing said holding means before said starting lug reaches 45 strip gripping engagement with said pressure roll during a feeding operation.

19. In a device of the character described, in combination, strip feeding mechanism including a feeding member having a strip gripping, feeding periphery adjacent to which is a strip engaging, starting lug and including also a pressure roll cooperating with said periphery and starting lug to form a feeding grip, strip engaging strip positioning means for positioning strips in feeding relation with reference to said feeding mechanism, means controlled by feeding actuation of 50 said feeding mechanism for retracting said positioning means from strip engaging position prior to engagement of said starting lug with said pressure roll during a feeding operation, a housing for said pressure roll, and a strip deflecting 55 plate positioned adjacent said feeding grip and extending rearwardly to present strip receiving passageways at the opposite sides thereof having receiving openings positioned at the rear of said housing so as to provide entry access of the strips 60 into the feed grip.

20. In a device of the character described, in combination, strip feeding mechanism including a feeding member having a strip gripping, feeding periphery adjacent to which is a strip en-

gaging, starting lug and including also a pressure roll cooperating with said periphery and starting lug to form a feeding grip, strip engaging strip positioning means for positioning strips in feeding relation with reference to said feeding mechanism, means for retracting said positioning means from strip engaging position prior to engagement of said starting lug with said pressure roll during a feeding operation, a housing 5 for said pressure roll, and a strip deflecting plate positioned adjacent said feeding grip and extending rearwardly to present strip receiving passageways having receiving openings positioned at the opposite sides thereof at the rear of said 10 housing so as to provide entry access of the strips into the feed grip, said deflecting plate having an opening into which said starting lug passes during feeding operation, said deflector plate at the forward terminal of said opening 15 presenting a concave marginal portion directed toward the forwardly feeding strips.

21. In a device of the character described, in combination, strip feeding mechanism including a feeding member having a strip gripping, feeding periphery and including also a pressure roll 25 cooperating with said periphery to form a feeding grip, a feed roll housing for said feed roll and a strip deflecting plate positioned adjacent to said feeding grip and extending rearwardly beyond said housing to present strip receiving passageways at the opposite sides thereof, said 30 passageways each having a receiving opening positioned at the rear edge of said housing so as to provide access for entering the strips into the feed grip without disturbance of said housing.

22. In a device of the character described, in combination, strip feeding mechanism including a feeding member having a strip gripping, feeding periphery and including also a pressure roll 40 cooperating with said periphery to form a feeding grip, a feed roll housing for said feed roll and a strip deflecting plate positioned adjacent to said feeding grip and extending rearwardly beyond said housing to present strip receiving passageways at the opposite sides thereof, said 45 passageways each having a receiving opening positioned at the rear edge of said housing so as to provide access for entering the strips into the feed grip without disturbance of said housing, said deflecting plate being movably mounted and having thereon a downwardly disposed strip deflector positioned adjacent to said feeding member for deflecting a lower strip downwardly upon 50 emergence thereof from the feeding grip.

23. In a device of the character described, in combination, strip feeding mechanism including a feeding member having a strip gripping, feeding periphery and including also a pressure roll 60 cooperating with said periphery to form a feeding grip, a feed roll housing for said feed roll and a strip deflecting plate positioned adjacent to said feeding grip and extending rearwardly beyond said housing to present strip receiving passageways at the opposite sides thereof, said 65 passageways each having a receiving opening positioned at the rear edge of said housing so as to provide access for entering the strips into the feed grip without disturbance of said housing, said deflecting plate having an opening receiving 70 said strip gripping feeding periphery, and a strip deflector positioned adjacent to said opening for deflecting a feeding strip away from the opening so as to avoid strip obstruction thereby.

75 24. In a device of the character described, in

combination, strip feeding mechanism including a feeding member having a strip gripping, feeding periphery and including also a pressure roll 5 cooperating with said periphery to form a feeding grip, a feed roll housing for said feed roll and a strip deflecting plate positioned adjacent to said feeding grip and extending rearwardly beyond said housing to present strip receiving passageways at the opposite sides thereof at the rear edge of said housing so as to provide access for 10 entering the strips into the feed grip without disturbance of said housing, said deflecting plate having an opening receiving said strip gripping feeding periphery, said deflecting plate at the forward terminal of said opening presenting a 15 concave marginal portion directed toward the forwardly feeding strips, and a strip deflector positioned adjacent to the forward terminal of said opening for deflecting a feeding strip away from the opening so as to avoid strip obstruction thereby.

25. In a device of the character described, in combination, strip feeding mechanism including a feeding member having a strip gripping, feeding periphery and including also a pressure roll 25 cooperating with said periphery to form a feeding grip, a feed roll housing for said feed roll, a strip deflecting plate positioned adjacent to said feeding grip and extending rearwardly beyond said housing to present strip receiving passageways 30 at the opposite sides thereof at the rear edge of said housing so as to provide access for entering the strips into the feed grip without disturbance of said housing, said deflecting plate having an opening receiving said gripping feeding periphery and a strip deflecting spring finger mounted on said deflector plate adjacent to the forward terminal of said opening for deflecting a feeding strip away from the opening so as to 35 avoid strip obstruction thereby.

40 26. In a device of the character described, in combination, strip feeding mechanism including a feeding member having a strip gripping, feeding periphery adjacent to which is a strip engaging, starting lug and including also a pressure roll 45 cooperating with said periphery and starting lug to form a feeding grip, a feed roll, a strip deflecting plate positioned adjacent to said feeding grip and extending rearwardly to present strip receiving passageways at opposite sides thereof, said 50 deflecting plate having an opening provided with a forward curved terminal for receiving said starting lug and said strip gripping, feeding periphery, and a strip deflector on said deflector plate positioned adjacent to said forward terminal of said opening for deflecting a feeding strip away from the opening so as to avoid strip obstruction thereby.

55 27. In a device of the character described, in combination, strip feeding mechanism including 60 a feeding member having a strip gripping, feeding periphery and including also a pressure roll cooperating with said periphery to form a feeding grip, a feed roll housing for said feed roll, a strip deflecting plate positioned adjacent to said feeding grip and extending rearwardly to present strip receiving passageways at the opposite sides thereof at the rear of said housing so as to provide access for entering the strips into the feeding grip, a writing plate positioned rearwardly 65 of said strip receiving passageways, a movably mounted strip positioning pin spaced rearwardly along said writing plate from said passageways, and retracting means for said pin operatively 70 75

controlled by strip feeding operation of said strip feeding mechanism.

28. In a device of the character described, in combination, strip feeding mechanism including a feeding member having a strip gripping, feeding periphery and including also a pressure roll cooperating with said periphery to form a feeding grip, a movably mounted feed roll housing for said feed roll, a strip deflecting plate positioned adjacent to said feeding grip and extending rearwardly to present strip receiving passageways at the opposite sides thereof at the rear of said housing so as to provide access for entering the strips into the feeding grip, a writing plate positioned rearwardly of said strip receiving passageways, a movably mounted strip positioning pin spaced rearwardly along said writing plate from said passageways, retracting means for said pin operatively controlled by said strip feeding mechanism, a latching device for holding said positioning pin in operative position, and means independent of said feeding mechanism for projecting said pin into operative, strip engaging position.

29. In a device of the character described, in combination, strip feeding mechanism, a movably mounted strip positioning pin spaced rearwardly from said feeding mechanism, means for setting said pin in strip engaging position, a pin holding device including a holding member for holding said pin in its operative strip engaging position, and operating means controlled by said feeding mechanism for releasing said holding member from pin holding position at one point of the operative feed cycle, and for holding said pin from projection into operative position at another point in said cycle.

30. In a device of the character described, in combination, strip feeding mechanism including a rotary feed disk, a movably mounted strip positioning pin spaced rearwardly from said feeding mechanism, means for setting said pin in strip engaging position, a pin holding device including a holding member for holding said pin in its operative strip engaging position, a plurality of operative elements mounted for movement with said feed disk, and operating means cooperating with one of said operative elements for releasing said holding member from pin holding position at one point of the operative feed cycle, and cooperating with another of said operating elements for holding said pin from projection into operative position at another point in said cycle.

31. In a device of the character described adapted to operate on a strip provided with perforations at intervals, in combination, strip feed mechanism including a feed roll adapted to interrupt the strip feed at the strip perforations, starting means controlled by said feed mechanism for starting the strips after the feed thereof has been interrupted, strip positioning means for positioning parts of the strips prior to entry thereof into said feed mechanism, and shifting means controlled by operation of said feed mechanism for shifting said strip positioning means so as to avoid strip positioning control thereby during the strip starting operation of said starting means.

32. In a device of the character described

adapted to operate on a strip provided with perforations at intervals, in combination, strip feed mechanism including a feed roll adapted to interrupt the strip feed at the strip perforations, starting means controlled by said feed mechanism for starting the strips after the feed thereof has been interrupted, strip positioning means for positioning parts of the strips prior to entry thereof into said feed mechanism, shifting means controlled by operation of said feed mechanism for shifting said strip positioning means so as to avoid strip positioning control thereby during the strip starting operation of said starting means, and means controlled by operation of said feed mechanism for preventing resetting of said positioning means at a predetermined point in the cycle of operation of said feed mechanism.

33. In a device of the character described adapted to operate on a strip provided with perforations at intervals, in combination, strip feed mechanism including a feed roll adapted to interrupt the strip feed at the strip perforations, starting means controlled by said feed mechanism for starting the strips after the feed thereof has been interrupted, strip positioning means including a movably mounted strip aperture engaging pin for positioning parts of the strips prior to entry thereof into said feed mechanism, and shifting means controlled by strip feeding operation of said feed mechanism for shifting said aperture engaging pin so as to avoid entry thereof into the strip aperture.

34. In a device of the character described adapted to operate on a strip provided with perforations at intervals, in combination, strip feed mechanism including a feed roll adapted to interrupt the strip feed at the strip perforations, starting means controlled by said feed mechanism for starting the strips after the feed thereof has been interrupted, strip positioning means including a movably mounted strip aperture engaging pin for positioning parts of the strips prior to entry thereof into said feed mechanism, and shifting means controlled by strip feeding operation of said feed mechanism for shifting said aperture engaging pin so as to avoid entry thereof into the strip aperture.

35. In a device of the character described adapted to operate on a strip provided with perforations at intervals, in combination, a writing plate or platen, strip feeding mechanism for feeding strips on said platen and including a feed roll adapted to interrupt the strip feed at the strip perforations, starting means controlled by said feeding mechanism for starting the strips after the feed thereof has been interrupted, means for positioning parts of the strips with reference to the platen including a movably mounted strip aperture engaging pin, said pin being positioned at the rear of the feeding mechanism beyond the writing surface of the platen, and shifting means controlled by strip feeding operation of said feeding mechanism for shifting said aperture engaging pin so as to avoid entry thereof into a strip aperture.

VICTOR WILLIAM GARWOOD.
